UNITED STATES PATENT OFFICE.

GEORGE N. BLANCHARD AND OTTO G. MINZENMAYER, OF SAN FRANCISCO, CALIFORNIA.

RECEIVER FOR TELEPHONES.

1,104,610.

Specification of Letters Patent. Patented July 21, 1914.

Application filed July 10, 1912. Serial No. 703,569.

To all whom it may concern:

Be it known that we, GEORGE N. BLANCHARD and OTTO G. MINZENMAYER, citizens of the United States, residing in the city and county of San Francisco and State of California, have invented certain new and useful Improvements in Receivers for Telephones, of which the following is a specification.

The hereinafter described invention relates to an improvement for increasing the intensity of the sound reproduction of telephone receivers, more especially those employing a horn for enlarging the volume of sound, and the object of the invention is to distinctly reproduce sounds and articulate speech sufficiently loud to be heard at a considerable distance by the attachment of a megaphone or horn to the receiver.

In receivers as ordinarily constructed, whether of single or double pole, the iron diaphragm acts as the armature for the magnet, which answers fairly well with the feeble current and consequent feeble magnetic effect induced in the receiver, but when more powerful results are desired it becomes necessary to have a path for the magnetic flux of greater cross section than the thin iron diaphragm affords.

To comprehend the invention, reference should be had to the accompanying sheet of drawings, wherein—

Figure 1 is a longitudinal sectional view of the improved receiver. Fig. 2 is an enlarged detail view of the magnet cores and the armature which coacts therewith.

In the drawings, the numeral 1 is used to indicate a suitable casing, preferably cylindrical in cross section and containing a mica or other non-magnetic diaphragm 2, which diaphragm is clamped or held at its periphery between two rubber washers 3 and 3' in any suitable manner, as by means of a threaded ring 4 which screws into the casing 1.

To the under face of the diaphragm 2 and centrally thereof is secured a wedge shaped iron armature 5, which in the present case is held to the diaphragm by a screw 6. This armature co-acts with two soft iron cores 7 and 7', which cores are secured in any suitable manner to the poles of a magnet 8, and the said cores are wound with the insulated wires 9.

The polar faces 9' of the cores 7 and 7' of the magnet 8 are shaped to conform to the sides of the wedge shaped armature 5, and

by reason of such construction of the polar faces of the cores 7 and 7' and the armature 5 it is possible to have ample cross section to carry the magnetic flux with a minimum weight, inasmuch as the armature, being in the shortest path which the magnetic flux can take, can be made exceedingly narrow and consequently very light in weight without undue magnetic leakage, the lightness of the armature being an important factor where the rate of vibration is high. Again, as the magnetic pull is at right angles to the armature sides, and as these sides are not parallel with the diaphragm, it is evident that the pull on the diaphragm is less than where the polar faces are parallel to the armature.

The strain on the diaphragm can be reduced to the proper degree by making the armature and the polar faces of the cores of proper angle relative to each other, and inasmuch as the air gaps are not parallel with the diaphragm, they are subject to less change in length of any given amplitude of vibration than when parallel with the diaphragm.

The magnet 8 with its cores 7 and 7' is adjustably supported from the casing 1 by any suitable means, as by the hangers 10, which are slotted at their lower ends to receive the set screws 11 for securing the magnet 8 thereto and holding the same in adjusted position. By thus giving adjustability to the magnet 8, the same may be so regulated as to place the wedge shaped armature 5 in very close proximity to the polar faces of the cores 7 and 7' without actually coming in contact therewith.

To the casing 1 is secured a horn or megaphone 12, through which the sounds reproduced by the receiver issue.

By means of the wedge shaped armature carried by the non-magnetic diaphragm of the receiver co-acting with the wedge or inclined polar faces of the magnet, the results obtained are far better than those flowing from the use of a flat armature carried by a lever coacting with the flat faces of the magnet cores, and the objectionable features of the weight and spring incident to the employment of a lever actuated flat armature are obviated.

By reason of the use of the double pole magnet and the wedge shaped armature, the polar faces of the magnet cores corresponding to the sides of the armature, the mag-

netic circuit is completed through iron and steel, excepting for the two air gaps, which have been shown to be exceedingly small, without the necessity of employing or using 5 an iron diaphragm.

The working parts of the instrument are inclosed or housed within an ordinary outer shell 12' to which the casing 1 carrying the diaphragm 2 and armature 5 is secured, the 10 said outer shell or housing being constructed of suitable material.

The instrument as constructed consists of but few parts, and as a whole the same is compact and rigid.

15 Having thus described the invention what is claimed as new and desired to protect by Letters Patent is—

In a receiver for the described purpose, the combination with a housing open at one 20 end, a disk-shaped hanger threaded into the open end of said housing and formed centrally with an opening, a bell mouth cover

secured to said disk-shaped hanger, arms extending into said housing from said disk-shaped hanger, a double pole magnet adjustably mounted on said arms, a non-magnetic diaphragm retained in position by the cover and extending over the opening in said hanger, a wedge shaped armature detachably carried by the under surface of said diaphragm, and cores carried by said magnet and extending through the opening in said hanger, the polar faces of which are shaped to conform to the side of the armature.

25 In testimony whereof we have signed our names to this specification in the presence of 30 two subscribing witnesses.

GEORGE N. BLANCHARD.
OTTO G. MINZENMAYER.
